COMBINATION SHAMPOO DISPENSER AND MASSAGE BRUSH

Donald D. Brown, 2448 W. Marian Ave.,
Anaheim, Calif. 92804

Filed Aug. 4, 1966, Ser. No. 3,339

Term of patent 14 years

(Cl. D9—2)

FIG. 1.

FIG. 2.

FIG. 6.

FIG. 3.

FIG. 4.

FIG. 5.

FIG. 1 is a front elevational view of a combination shampoo dispenser and massage brush, showing my new design;

FIG. 2 is a rear elevational view thereof;

FIG. 3 is a side elevational view thereof taken from the right of FIG. 1;

FIG. 4 is a top plan view thereof;

FIG. 5 is a bottom plan view thereof; and

FIG. 6 is a bottom perspective view thereof.

The side not shown has substantially the same appearance as the side shown.

I claim:

The ornamental design for a combination shampoo dispenser and massage brush, substantially as shown and described.
